UNITED STATES PATENT OFFICE.

FRANCESCO CIRELLI, OF PHILADELPHIA, PENNSYLVANIA.

TALKING MACHINE.

1,412,166.

Specification of Letters Patent. Patented Apr. 11, 1922.

Application filed July 29, 1920. Serial No. 399,646.

To all whom it may concern:

Be it known that I, FRANCESCO CIRELLI, a subject of the King of Italy, residing at Philadelphia, in the county of Philadelphia and State of Pennsylvania, have invented certain new and useful Improvements in Talking Machines, of which the following is a specification.

One object of my invention is to provide a talking machine which can be easily carried and which will be so constructed that if not desired for use the parts thereof can be arranged and held in a compact form within the casing.

Another object is to so construct said casing that it will serve as an exceptionally good resonant support for the tone reproducing elements when the machine is in operation.

A still further object is to provide said casing with a lid which will be bound thereto through the medium of the center post of the record-supporting turntable and to so construct said lid that it will be placed under resilient tension due to its connection with said center post so that the parts will not rattle while being carried or transported and so that a number of records can be safely carried in the casing.

These objects, and other advantageous ends which will be described hereinafter, I attain in the following manner, reference being had to the accompanying drawings in which—

Figure 1 is a side elevation of my improved talking machine with the operative parts removed from the casing and in the position which they occupy during the operation of the machine.

Figure 2 is a top plan view of Figure 1.

Figure 3 is a sectional elevation taken on the line 3—3 of Figure 2,

Figure 4 is a sectional plan view taken on the line 4—4 of Figure 3,

Figure 5 is a detached elevation showing certain of the parts in central section and illustrating the arrangement of the removable parts in the order or position in which they occupy when either arranging the machine for operation or for transporting purposes,

Figure 6 is a sectional elevation showing the parts illustrated in Figure 5 in their position when the machine is closed so that all parts are retained within the casing,

Figure 7 is a sectional plan view taken on the line 7—7 of Figure 1 and drawn on a smaller scale,

Figure 8 is a perspective view of my improved machine as it appears when the casing is entirely closed with all of the elements contained therein,

Figure 9 is a fragmentary elevation, partly in section, showing how the tone arm is constructed to permit the sound box to be stored therein, and

Figure 10 is a view showing said sound box in its position within the storing space of the tone arm.

Referring to the drawings, 11 represents a substantially cylindrical drum or casing which is preferably made of sheet metal closed at its bottom and side; said side 12 being preferably reinforced by producing annular ribs 12^a. A circular top board 13, which is preferably made of wood, rests upon an internal flange 14 which extends within the casing as clearly shown in Figures 5 and 6. The upper edge of the side 12 is bent outwardly immediately above the flange 14 as shown at 15 and then inwardly to provide an inwardly projecting flange or ledge 16. The top board 13 has its outer edge positioned in the space provided within the portion 15 and under the flange 16 and a top plate 13^a forms a covering for the top board 13. The interior of the drum 11 includes two partitions 17 and 18 which are arranged as illustrated in dotted lines in Figure 7 and in full lines in Figure 4 to provide two compartments 19 and 20.

By thus arranging the partitions 17 and 18 a large compartment 21 is provided which includes the axis of the drum 11 and within this compartment 21 is located the driving motor 22 which is diagrammatically represented in dot-and-dash lines and which serves to rotate a turntable supporting center post 23; said center post leading upwardly through the top board 13 and top plate 13^a as clearly shown in Figures 3, 5 and 6.

The center post 23 has an enlargement 24 and a record-supporting turntable 25 which may be placed over said center post rests on said enlargement 24 above the level of the top plate 13^a so that during the rotation of the center post by the motor, the turntable will also be rotated in the usual manner. The compartment 21 includes an extension 1105 1110

21^a which leads outwardly toward the side of the drum 11 between the compartments 19 and 20; said partitions 17 and 18 being bent for this purpose as clearly shown in Figure 5 4. Any suitable regulating means such for example as that shown at 26 may be placed upon the top plate 13^a at a position beyond the outer edge of the turntable to permit the manipulation of the adjusting means and 10 said means can be located in the extension 21^a of the compartment 21.

The side 12 of the drum 11 has an opening 27 in alignment with the winding shaft 28 of the motor 22 so that a winding crank 15 or handle 29 can be inserted through the opening 27 to operatively engage the winding shaft 28 to wind the motor. When not desired for use the handle 29 can be removed and the opening 27 can be closed by a 20 cap 30 as shown in Figure 8. A stanchion plate 31 is secured to the top plate 13^a beyond the outer edge of the turntable and this stanchion plate includes a screw threaded hole 32 in which a stanchion or tone 25 arm supporting post 33 is screwed; said post 33 extending upwardly within a tone arm or horn 34 so that said tone arm is free to swing on the top of the pivot post 33; the pivot connection being between the ends 30 of the tone arm as clearly shown in Figure 1.

The tone arm is tapered and at its narrow end has a cross head 35 in which is pivoted a hollow extension 36 which has the sound box 37 mounted thereon for reproducing 35 engagement with a record 38 which is mounted upon the turntable 25. It will thus be noted that the tone arm is adapted to swing in a horizontal plane while the extension 36 and sound box 37 is capable of swinging 40 in a vertical plane. The outer edge of the portion 40 of the tone arm 34 includes a perforated plate 41 as clearly shown in Figures 9 and 10; said plate extending or bulging inwardly and spaced inwardly 45 from the extreme outer edge of the tone arm. A perforated cap 40^a snugly fits the end portion 42 of the tone arm and a chamber 43 is thus produced in which the sound box 37 can be stored and safely kept when not desired 50 for use; the inwardly bulged character of the perforated plate permitting the usual connecting flange 44 of the sound box to be located in a position so as to keep the sound box in a substantially transverse position and to prevent it from rocking or becoming injured while contained in its stored 55 position.

The top board 13 and top plate 13^a have a hole 45 extending therethrough directly 60 over the compartment 19 to permit the pivot post 33, winding handle 29 and the tone arm, with the sound box stored therein, to be placed within the compartment 19 when said parts are not desired for use; such arrangement being illustrated in Figures 5

and 6. The compartment 20 may be employed for storing or carrying any other articles desired.

A lid 46 which is preferably made of sheet metal and of circular formation includes a downwardly extending flange or rim 47; said rim bulging outwardly and then inwardly at its lower edge as shown at 48. The lower edge 48 is adapted to rest upon the top and innermost part of the flange or ledge 75 16; the arrangement being such that any pressure upon the top of the lid will tend to slightly move the lower edge portion 48 of the lid inwardly due to the slight flexing of the rim 47 as is obvious from 80 the illustration of Figure 6. The top of the lid is pressed to provide a number of concentric ribs 49 and the innermost or central portion 50 of the top of the lid includes a hole 51. The center post 23 is made 85 comparatively high and extends a considerable distance above the turntable. The top end of the center post includes a tapped or screw threaded hole 52 into which the screw threaded stem of a thumb screw 53 fits; said screw threaded stem of the thumb screw extending through the hole 51 in the lid 46. The central portion 50 is normally above the top of the center post 52 so that in inserting the thumb screw 53 the head of 90 said thumb screw will engage the central portion 50 and move the latter downwardly to cause the top of the lid to be placed under tension and the lower edge 48 of the rib to be held in firm contact with 95 the top of the casing. By providing the top of the lid with the ribs 49 the top is strengthened but at the same time permits the resilient flexing of the top of the lid so that the lid will be firmly held in place. 100 The pitch of the screw threads of the screw 53 and hole 52 in the center post preferably is such that any accidental attempt of the center post to rotate by the action of the motor will be stopped due to the increase of 105 tension placed upon the lid as is obvious for the fact that the thumb screw 53 will tend to tighten within the tapped hole 52 of the center post. The top of the lid 46 is preferably spaced at such distance 110 from the turntable that a number of records can be stored on the turntable as shown in Figure 6 and all of the parts will be held in a firm position when the lid is in place. 115

Any suitable brake, such for example as 120 shown at 54, can be employed and the drum is preferably provided with transversely extending bars 55 which are spaced apart and serve as feet to permit the drum to be stood up on its side as shown in Figure 8. A 125 handle 56 is also preferably connected to the drum for the purpose of carrying the machine.

The parts are so constructed and arranged 130 that they may be quickly placed in operative

position or they may be quickly and easily stored within the casing so that the device is especially adapted for use when it is necessary to carry the machine from place to place and it can be used with advantage at seashore resorts or during vacation periods where a readily portable machine is desired.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

20 1. A talking machine including a casing; a motor secured within the casing and having a rotatable post; a lid having a resilient portion and another part for engagement with said casing; and means for clamping said resilient part of the lid to said post whereby said resilient part will be placed under tension; substantially as described.

25 2. A talking machine including a casing; a motor secured within said casing and having a rotatable post; a turntable supported by said post, said post having a portion projecting beyond the supporting surface of the turntable whereby a number of records can be placed upon the turntable in superimposed 30 position and in which the projecting por-

tion of the post extends through said records; a lid for said casing and having a resilient portion opposed to said supporting surface of the turntable; and means for clamping said resilient portion of the lid to 40 said post, said resilient portion of the lid having circular ribs formed therein; substantially as described.

3. A talking machine including a casing; a motor secured within said casing and having a rotatable post; a lid for said casing, said lid having a rim outwardly bulged for engagement with said casing; and means for clamping said lid to said post whereby said flange will be compressed into tight fitting 45 50 engagement with said casing; substantially as described.

4. A talking machine casing having a body portion closed at its bottom and open at its top, the top edge of said portion having an inwardly extending flange; and a top board supported by said flange, said body portion having another flange terminating in a free edge independently of said first flange and surrounding the edge of said top board 55 60 and secured thereto; substantially as described.

In testimony whereof I have signed my name to this specification in the presence of two subscribing witnesses.

FRANCESCO CIRELLI.
